UNITED STATES PATENT OFFICE.

WALTER H. DIFFENDALL, OF HAGERSTOWN, MARYLAND.

RIVET-HEATING FURNACE.

1,231,507.

Specification of Letters Patent. Patented June 26, 1917.

Application filed March 9, 1917. Serial No. 153,598.

To all whom it may concern:

Be it known that I, WALTER H. DIFFENDALL, a citizen of the United States, residing at Hagerstown, in the county of Washington and State of Maryland, have invented certain new and useful Improvements in Rivet-Heating Furnaces; and I hereby declare that the following is a full, clear, and exact description thereof, reference being had to the accompanying drawings, which form part of this specification.

This invention is a novel portable furnace, especially designed for heating rivets, such as are used in structural iron work.

15 The furnace is designed to be heated by oil, or hydrocarbon mixtures, or gas.

The object of the invention is to produce a furnace which is not complicated; which can be easily operated, and can be easily repaired, and the parts replaced if damaged; and which can be readily adapted for heating different sizes of rivets quickly and economically.

I will explain a practical embodiment of 25 the invention, illustrated in the accompanying drawings, in detail and refer to the claims for summaries of the essential features and combination of parts for which protection is desired.

30 Referring to the accompanying drawings: Figure 1 is a vertical sectional elevation of the complete furnace.

Fig. 2 is a detail top plan view.

Fig. 3 is a view of the lower half of the 35 furnace with the top portion removed.

Fig. 4 is a detail sectional view taken on line 4—4 of Fig. 3.

The furnace proper consists of a cylindrical body comprising an upper section 4 and 40 a lower section 5. The lower section 5 is annular, and is preferably supported upon four legs 8, which may be made of pipe and the upper ends of these legs are inserted in sockets 5^a in the section 5 and secured there- 45 in by tap bolts 5^b as indicated in Figs. 3 and 4.

The interior of section 5 is preferably tapered or conical, being larger in diameter at bottom than at top; and this section may 50 be provided with a plurality of perforated ears or lugs 5^c on its outer side, as in Fig. 3, for a purpose hereinafter referred to. The section 5 may also be provided with an annular rib 5^e on its upper side adapted to 55 interlock with a corresponding rib 4^e on the upper section 4 of the casing.

The upper section 4 of the furnace is preferably cylindrical, and is mounted upon the section 5, resting upon the rib 5^e and having a flange 4^d interlocking with rib 5^e 60 as shown in Fig. 1. Said upper section has a series of perforated lugs or ears 4^c on its lower end opposite the perforated lugs 5^c on the lower section; and the sections 4 and 5 may be firmly but detachably united by 65 means of bolts 3 passed through the opposed lugs 4^c, 5^c and secured by nuts 3^a as shown. The section 4 also has on its upper end a series of perforated lugs 4^f.

The section 4 may be provided with eyes 70 4^g on its sides to facilitate handling or transport of the upper section, or of the furnace.

On the upper end of the section 4 is a cover plate 1 which is removable; this plate may be of any desired shape, but is shown 75 as flat. It is provided with a series of perforations 1^f which are adapted to come opposite the perforated lugs 4^f, and the top plate may be detachably secured to the section 4 by means of bolts 2 passed through 80 the perforations 1^f and lugs 4^f, which bolts may be fastened by keys 2^a as indicated in the drawings, or by other suitable means.

The top plate 1 is provided with a series of 85 perforations 1^b which are preferably slightly larger in diameter than the shanks of the rivets to be heated, but smaller than the heads of such rivets, so that a series of rivets to be heated may be suspended in the furnace from the top plate in position to be heated by dropping their shanks through the openings 1^b as indicated in Fig. 1 while the heads of the rivets close the openings. If desired a refractory packing 1^e of any 90 suitable material may be interposed between the upper ends of the section 4 and the plate 1.

The plates 1 are made interchangeable. A plate having openings corresponding to the size of the shanks of the rivets to be heated should be used. These plates can be readily interchanged, and one having openings of the desired size fastened to the section 4. If small rivets are used 100 plates with small openings will be provided, if larger rivets plates with larger openings 105 will be used.

The burner or gasifier is preferably formed of a pipe coiled upon itself into a flat coil as shown at 6 in Figs. 1 and 3, and having a central upstanding portion 6^a on which is fitted a cap 6^b that is suitably per-

forated to permit the escape of gases through the coil into the lower part of the furnaces. The burner 6 may be detachably attached to and suspended from the section 5 of the furnace by means of a U-shaped hanger, or hangers, 6^a, the ends of which may be fastened to the section 5 by means of bolts 6^a. The end 6^a of the burner carrying the jet head 6^b is preferably arranged in 10 the axial line of the furnace.

Fuel may be supplied to the burner by a pipe P from any suitable supply, and the fuel can be mixed with air if desired before reaching the burner, by any suitable apparatus; which apparatus can be located at any desired distance from the furnace. The outer member 6^c of the coil may be detachably connected with the supply pipe P by means of a coupling 6^d. In this way the oil 15 tank or fuel supply can be located at any desired distance from the furnace so that there will be no danger of overheating the oil or gas in the tank, or ignition of the fuel within the tank. A pan 9 for catching scale 20 or oil drippings may be mounted on the legs 8 beneath the burner 6 as indicated in Fig. 1.

If desired a control valve 6^e may be placed in the pipe 6^c so that the operator can cut 30 off the supply of fuel to the burner at the furnace, in case the latter is located at a distance from the fuel supply or from the usual regulating valves, or in case of emergency.

35 When the furnace is fired the heating flame is directed upwardly against plate 1 and part of the heat is reflected downward and heats the burner 6 gasifying the fuel.

The furnace is cheaply constructed and 40 easily repaired; and if either section 4 or 5 should burn out, or be injured in any manner, it can be readily replaced by a duplicate section.

Sufficient air for combustion is supplied 45 through the space between the burner 6 and the lower end of the section 5.

By means of the interchangeable top plates the furnace can be very easily adjusted for heating rivets of any desired size.

50 The rivets cannot fall into the fire; the workman is protected from a great deal of the heat; and the ends of the shanks of the

rivets (which are the main parts to be heated) are directly subjected to the most intense heat, while the heads practically remain comparatively cool. 55

What I claim is:

1. A rivet heating furnace comprising a body composed of upper and lower annular sections having interlocking ribs and perforated lugs on their meeting ends, bolts engaging said lugs and connecting the sections together, a top plate detachably attached to and closing the upper end of the body and having openings through which the shanks of the rivets may be passed to suspend the rivets within the upper section, and a burner beneath the lower section and discharging into the furnace. 60

15 2. A rivet heating furnace comprising a body composed of upper and lower annular sections provided with perforated lugs on their meeting ends, and bolts transfixing these lugs and connecting the sections together, said upper section also having perforated lugs near its upper end; a top plate closing the top of the upper section and attached thereto by bolts engaging the lugs on the upper end of said section, said plate being perforated for the passage of the shanks of the rivets; and a burner discharging into the furnace. 75

3. A rivet heating furnace, comprising a body composed of upper and lower annular sections having interlocking ribs on their meeting ends and radially projecting perforated lugs adjacent the ribs, and bolts transfixing said lugs and connecting the sections together; said upper section also having perforated lugs near its upper end; a top plate closing the upper end of the furnace and detachably attached thereto by bolts engaging perforations in the plate and the lugs on the upper end of the upper section; said plate being provided with perforations for the passage of the shanks of the rivets, and means connected with the lower section for supporting the furnace, and a burner suspended beneath the lower section and discharging into the furnace, 100 substantially as described. 95

In testimony that I claim the foregoing as my own, I affix my signature.

WALTER H. DIFFENDALL.
